UNITED STATES PATENT OFFICE.

MAURICE S. WALKER, OF BROOKLINE, MASSACHUSETTS.

DESIGN FOR A BOTTLE.

Application filed June 17, 1926. Serial No. 18,072. Term of patent 3½ years.

To all whom it may concern:

Be it known that I, MAURICE S. WALKER, a citizen of the United States, residing at Brookline, in the county of Norfolk and State of Massachusetts, have invented a new, original, and ornamental Design for a Bottle, of which the following is a specification, reference being had to the accompanying drawing, forming part thereof.

Figure 1 is a front elevation of the improved bottle and ornamentation therefore.

Figure 2 is a top plan view thereof.

My design consists of the combination of a bottle 10 of a deep amber color having attached thereto a label 11 which has a white border separated from the interior thereof by a gold band, the interior of the label

being divided into three vertically elongated panels separated by vertical gold lines, the end panels being white while the middle panel is a combination of green and white.

A second label 12 is also attached to the bottle 10 above the label 11 and has a white border separated from the interior thereof by a gold band. The interior of the label is a combination of green and white.

The bottle 10 is provided with a green cap 13 and covering the lower edge of the cap and the upper end of the bottle is gold colored tinfoil 14.

I claim:

The ornamental design for a bottle substantially as shown and described.

MAURICE S. WALKER.
